UNITED STATES PATENT OFFICE.

CHARLES EVAN FOWLER, OF NEW YORK, N. Y.

CONCRETE PILE.

Application filed July 14, 1925. Serial No. 43,581.

My invention relates to a concrete pile and particularly to a pile so formed as to have increased holding attributes when driven as well as possessing a form to resist driving or bending stresses when being driven.

An important object of my invention is to provide a concrete pile so formed as to have an increased lateral frictional surface whereby to resist any loosening tendencies and thereby to lend stability to the pile when driven.

A further object of the invention is to provide a concrete pile having a formation at the upper portion of a character to resist blows and force exerted thereon in driving the pile and at the same time equipped with a lower portion to readily enter the ground.

The nature of the invention and its distinguishing features and advantages will clearly appear as the description proceeds.

Reference is to be had to the accompanying drawings forming a part of this specification, it being understood that the drawings are merely illustrative of practical examples of the invention.

Figure 1 is a side elevation of a concrete pile formed in accordance with my invention;

Figure 2 is an enlarged plan view thereof;

Figure 3 is a cross section on the line 3—3, Figure 1;

Figure 4 is a side elevation modified as to the distance to which the upper portion is carried along the pile;

Figure 5 is an elevation of the lower portion of the concrete pile modified as herein-after explained.

In carrying out my invention in the form shown in Figures 1 to 3, the upper portion 10 of the pile is formed of a polygonal cross section and solid. The solid polygonal section extends comparatively a short distance sufficient to resist the blows and bending stresses in the region of the upper portion of the pile. The lower portion of the pile below the head 10 is cruciform in cross section as shown best in Figure 3, whereby the pile presents two webs 12 at right angles or approximately so, and integral with a solid central portion 13. The bottom edges of the webs 12 are sharpened as at 14. In the pile as formed in Figures 1 to 3 the lower sharpened edges 14 of the respective webs 12 terminate in the same plane whereas in Figure 5 the pile is formed with transverse webs 112 at right angles to each other following the general cruciform shape of the first-mentioned form

but in the form of Figure 5, the webs 112 integral with a central solid portion 113 terminate as at 114 in different planes, the one web 112 extending below the other as will be clear from an explanation of Figure 5. The webs 12 have in practice vertical reinforcing rods 15 and also the head or polygonal upper portion 10 has additional reinforcing elements 16 adjacent to each side face thereof.

In the form shown in Figure 4 the solid polygonal upper portion 110 corresponding in purpose and mode of functioning with the head 10 extends to a greater distance along the pile so that the lower end of said head extends below the ground. The carrying down of the solid polygonal portion to a greater length as shown in Figure 4 than the form shown in Figure 1, resists the bending stresses to a greater degree than the mere driving head 10. In Figure 4 the numeral 212 indicates the webs which, owing to the carrying down of the head 110, are shorter than the webs 12. The numeral 14 indicates the sharpened lower cutting edges of the webs 212, said lower edges corresponding with the edges in Figure 1.

Shoes, in practice, may be provided on the lower cutting edges of the piles of any one of the forms described and illustrated. In Figure 5, the numeral 17 indicates the shoes on the lower edges of the webs and present cutting edges to cut through stiff material.

It will readily be understood that with a concrete pile having the cruciform cross section and the central solid portion, the maximum lateral friction surface is provided whereby to exert a holding action on the pile when in the ground. Moreover, the sharpened edges 14 and the shoes enable the pile to be readily driven into the ground resistant of the driving of concrete piles of ordinary form.

It is to be noted that, as best shown in Figure 2, the head 10 is polygonal, and specifically said head is octagonal. Also it will be noted that the faces disposed at the top and bottom of Figure 2 are broader than the two lateral faces in planes at right angles to said top and bottom faces. The faces represented at the top and bottom of Figure 2 are in practice disposed at the front and back of the pile, so as to take the bending stresses of waves or tides, for example. The broad front and back surfaces thus provided permit of reinforcing members being disposed in a series, in a plane substantially parallel

with said front and back faces, there being three reinforcing elements it will be noted, represented at the top and bottom of Figure 2. The provision of broad front and back faces to take bending strains making it possible to employ a plurality of reinforcing members adjacent the said faces to resist said bending strains, contributes materially to the embodiment of strength in the pile.

10 I would state furthermore that while the illustrated examples constitute practical embodiments of my invention, I do not limit myself strictly to the exact details herein illustrated, since, manifestly, the same can be 15 considerably varied without departure from the spirit of the invention as defined in the appended claims.

Having thus described my invention, I claim:

20 1. A concrete pile having a lower portion cruciform in cross section, and a solid driving head at the upper portion and extending laterally outward over said cruciform lower portion to receive driving blows and protect 25 said lower portion.

2. A concrete pile cruciform in cross section in its lower portion to present transverse

webs at approximately right angles to each other, the lower ends of said webs being individually sharpened, the upper portion of 30 said pile being solid.

3. A concrete pile cruciform in cross section in its lower portion to present transverse webs at approximately right angles to each other, the lower end of each of said webs being sharpened and the said sharpened ends tapering from opposite sides, the upper portion of said pile being solid and of polygonal cross section.

4. A concrete pile having a lower portion 40 cruciform in cross section to present webs at approximately right angles to each other, said webs having therein vertical reinforcing rods, the upper portion of said pile being solid and having vertical reinforcing rods additional to the first-mentioned reinforcing rods and terminating at said head.

5. A concrete pile having webs extending laterally along the lower portion of the pile at angles to each other, the lower edges of said webs presenting transverse individual cutting edges, said cutting edges alining in pairs. 50

CHARLES EVAN FOWLER.
